PLASMA WELDING TORCH

William J. Dahlman, Sylmar, and Lee F. Budds, Canoga Park, Calif., assignors to North American Rockwell Corporation

Filed July 3, 1968, Ser. No. 12,625

Term of patent 14 years

Int. Cl. D15—05

U.S. Cl. D26—1

FIG. 1

FIG. 2

FIG. 3

FIG. 4

FIG. 5

FIG. 1 is a perspective view of a plasma welding torch showing our new design;

FIG. 2 is a side elevational view;

FIG. 3 is a top plan view;

FIG. 4 is a bottom plan view, and

FIG. 5 is an end view.

The fragmented disclosure of flexible supply lines at the right of FIGS. 1—4 and FIG. 5 is for convenience of illustration only.

We claim:

The ornamental design for a plasma welding torch as shown.
